UNITED STATES PATENT OFFICE.

CHARLES A. ROSENTHAL, OF NEW ORLEANS, LOUISIANA.

GAME BOARD.

Application filed September 22, 1923. Serial No. 664,289.

To all whom it may concern:

Be it known that I, CHARLES A. ROSENTHAL, a citizen of the United States, residing at New Orleans, in the parish of 5 Orleans and State of Louisiana, have invented new and useful Improvements in Game Boards, of which the following is a specification.

My present invention pertains to game 10 boards, and it contemplates the provision of a game that requires a certain amount of skill in order to successfully accomplish the object thereof, and one adapted for use at home as well as at amusement parks 15 and the like.

Other objects and characteristic advantages will be fully understood from the following description and claim when the 20 same are read in connection with the drawings accompanying and forming part of this specification, in which

Figure 1 is a plan view of the board and showing same partly in section.

Figure 2 is a longitudinal section on line 25 2-2 of Figure 1.

Figure 3 is a transverse section on line 3-3 of Figure 1.

Similar numerals of reference designate 30 corresponding parts in all the views of the drawings.

My novel board consists of a casing comprising a base 1 and sides 2, as well as up-standing ends 3 and 4 and the said sides 2 are grooved at 5 to receive a glass top 6 that is open in one corner as indicated by 7, whereby the marbles may if desired, be 35 removed from the board by turning the board upside down.

The forward end portion 4 is provided 40 in its center with an opening 8 while arranged in rear of the opening 4 on the base 1 is a baffle 9 and the base 1 is further provided with the recesses 10 and at the rear of the recesses 10 I provide a channel or gutter 11.

The base 1 is also provided with the staggered pins 12.

It will be noted that the recesses are provided with small symbols *s* whereas placed 50 on the board immediately to the side of each recess are symbols *S*.

The small symbols reading up and down that are in the recesses, spell the word

"Gotit", and likewise the symbols adjacent to the recesses reading across the board, 55 spell the word "Gotit".

In playing the game each player is given five marbles that are put into the opening 8, one at a time, and each ball is guided by the player to the recess he is trying to make. 60 Each of the players has a separate board and they start and stop playing at the same time and when a player is first to manipulate the board so that the marbles are positioned to make the word "Gotit", either 65 up and down or across or diagonally of the board he is the winner of the game.

In the center recess counting from all angles of the recesses I fixedly secure one marble and hence a player may use only 70 four of his five marbles to spell the word "Gotit" if he is fortunate enough to drop his marbles in the center row of recesses, both up and down or diagonally of the board. Hence there are four ways in which 75 only four marbles may be used to spell the five lettered word "Gotit" while there are seven ways in which five marbles are required.

If a player loses control and the ball 80 passes by all of the recesses, it will fall into the gutter at the bottom of the board, and is lost. The ball can only be regained by turning the board upside-down and in doing so he will displace all of the balls he has 85 already lined up. The loss of one marble does not mean the loss of the game as it will be seen that four of the rows require only four marbles, as before set forth. Manifestly the marbles may be recovered 90 through opening 8.

It will be manifest from the foregoing that the game is extremely simple and interesting to play and calculated to excite quite an amount of rivalry among the players. 95

Having described my invention, what I claim and desire to secure by Letters Patent is:—

In a game board, the combination of a 100 casing having a base and side and end boards, an aperture formed in one end board, a cover arranged on the casing and having an opening, a plate formed on the base in rear of the opening of the end portion, pins 105 arranged on the base in rear of the plate, re-

cesses arranged on the base in rear of the pins, a gutter formed in rear of the recesses, said recesses being provided with symbols and other symbols arranged outside the recesses, substantially as and for the purpose set forth.

In testimony whereof I have hereunto set

my hand in the presence of two subscribing witnesses.

CHARLES A. ROSENTHAL.
